COMBINED UMBRELLA AND SHEATH

Manfred Bremshey, Mount Royal, Quebec, Canada, assignor to Telesco Brophey Limited, Montreal, Quebec, Canada

Continuation-in-part of design application Ser. No. 14,441, Nov. 13, 1968. This application Jan. 21, 1970, Ser. No. 21,017

Claims priority, application Canada June 5, 1968

Term of patent 14 years

Int. Cl. D3—99

U.S. Cl. D87—1

FIG. 1 is a perspective view of the combined umbrella and sheath;

FIG. 2 is a plan view of the combined umbrella and sheath shown in FIG. 1;

FIG. 3 is a side elevational view thereof;

FIG. 4 is an end elevational view thereof; and

FIG. 5 is an elevational view taken from the other end of the combined umbrella and sheath.

I claim:

The ornamental design for a combined umbrella and sheath, as shown.
